UNITED STATES PATENT OFFICE.

AXEL E. OLSSON, OF CHICAGO, ILLINOIS, ASSIGNOR TO S. KARPEN & BROS.,
OF CHICAGO, ILLINOIS, A COPARTNERSHIP.

DESIGN FOR A LEG FOR COUCHES.

SPECIFICATION forming part of Design No. 35,726, dated February 11, 1902.

Application filed June 17, 1901. Serial No. 64,966. Term of patent 3½ years.

To all whom it may concern:

Be it known that I, AXEL E. OLSSON, a citizen of the United States, residing at Chicago, county of Cook, and State of Illinois, have invented and produced a new and original Design for Legs of Couches, of which the following is a specification, reference being had to the accompanying drawings, forming a part thereof, and in which—

10 Figure 1 is a front elevation of a leg embodying my invention. Fig. 2 is an end elevation drawn to a reduced scale.

The leg comprises a lower portion or base of Italian renaissance, being a number of 15 claw-legs A A in bold relief. These are bound together at their upper ends by the band D, and this band has its ends interlaced. The upper portion of the design is in relief less bold than the claw-legs and is a symmetrical representation of short conventionalized 20 acanthus-leaves B, with drooping ends at the top of the leg, all grouped about a rosette C in the center of the foliage, said rosette be-

ing a conventionalized acanthus - blossom. The upper end of the leg is of less width than 25 the lower end, and the middle part of the leg is of less width than said upper end, appearing to be drawn in by the band D.

The essential features of my design are the broad lower or base part representing a number 30 of claw-legs surmounted by the narrower upper part, representing conventionalized foliage clustered about a center rosette, all of said parts being in relief.

Having described my invention, what I 35 claim as new, and desire to secure by Letters Patent, is—

The design for a leg for couches, substantially as herein shown and described.

In witness whereof I have signed my name 40 to this specification in the presence of two subscribing witnesses.

AXEL E. OLSSON.
